UNITED STATES PATENT OFFICE.

GEORGE A. SIMMONS, OF PORTLAND, OREGON.

GAS FURNACE.

Application filed April 28, 1925. Serial No. 26,369.

This invention relates generally to furnaces employing gas for house heating, and particularly to gases formed from oils.

The object of this invention is the construction of an exceedingly simple and efficient type of warm air furnace which can be constructed at a relatively low cost and which is so designed as to condense certain of the gases and vapors which are ordinarily carried off by way of the smoke pipe, and to remove same from the furnace by gravity instead of attempting to drive same off by heat or permitting same to remain within the furnace and attack the metal structure thereof.

The second object is to so construct the furnace that it will be exceedingly easy to clean and at the same time make same capable of handling a relatively large volume of air in proportion to its size.

These results are attained in the manner specified in the following specification as illustrated in the accompanying drawings, in which:

Figure 1 is a front elevation of the furnace of which Figure 2 is a horizontal section taken along the line 2-2 in Figure 3. Figure 3 is a vertical section taken along the line 3-3 in Figure 4. Figure 4 is a vertical section taken along the line 4-4 in Figure 3.

Similar numbers of reference refer to the same parts throughout the several views.

Referring in detail to the drawings, the furnace consists of a rectangular combustion chamber 10 having a side opening projection 11 formed on the front thereof. The projection 11 is provided with flanges 12 around its sides. The top 13 of the member 10 is closed. On the bottom 14 of the combustion chamber 10 is placed a burner base 15 to which are secured the burner pipes 16 by means of the straps 17.

Alongside of the combustion chamber 10 and spaced therefrom is a condensing chamber 18 connected with the combustion chamber by means of the two tubes 19 near the upper ends of both bodies. The horizontal smoke pipe 20 for carrying off the burned gases turns downwardly through the top 21 of the condensing chamber 18 and has hung from its lower end 22 a relatively flat funnel 23 by means of the straps 24. A hole 25 is formed in the bottom 26 of the condensing chamber 18 and connects with the funnel 27 of the condensation pipe 28 which

opens into a sewer or receptacle outside of the furnace. Legs 29 and 30 support the members 10 and 18 on the floor.

Around the combustion chamber 10 and the condensing chamber 18 is placed a casing whose side walls 31 are provided with insulation 32 along their upper portions, which insulation is further lined with a metal casing 33.

The smoke pipe 20 projects through one side 34 of the casing. A clean-out door 35 is provided which also acts as a support for the condensation pipe 28. The cold air duct 36 can be admitted through the most convenient side 31.

A door frame 37, preferably cast in aluminum and provided with a door 38, is placed against a hole in one of the sides 31 in front of the projection 11 and is secured to the flanges 12.

The top 39, which serves as a pan for the sand 40, also serves as a starting point for the various runs of warm air pipe 41.

The operation of the furnace is as follows: When gas is burned at the burners 16 the heat of the burning gases is radiated through the walls of the combustion chamber 10 into the surrounding air which is entering through the cold air pipe 36, causing same to rise and pass out by way of the warm air pipes 41 in the usual manner. The burned gases now pass through the tubes 19 of the condensing chamber 18 where they give off still more of the heat; the coldest of these gases settling downwardly into the condensing chamber under the pressure of other burned gases, and finally make their escape through the open end 22 into the smoke stack or outside atmosphere.

It will be seen that the temperature of these burned gases have thus been rapidly lowered to a point where they will liquefy. If this transpires within the condensing chamber, or as will most likely be the case in the vertical portion of the smoke pipe 20, the liquids thus formed will be carried by gravity to the condensation pipe 28 by means of which they are withdrawn from the furnace.

It will thus be seen that instead of carrying the stack temperature of the furnace at a height sufficient to carry off the heavier gases and vapors always accompanying the combustion of gases made from oil, that the stack temperature may well be lowered to a point which is only sufficient to stimu-

late a draft capable of carrying away such gases which will not readily condense.

Since one of the greatest difficulties encountered in the construction of furnaces for the burning of oil gas is due to the destructive nature of the gases themselves, it is evident that by this construction the great difficulty in this type of furnace is overcome.

10 I am aware that many forms of gas furnaces have been constructed in the past; I therefore do not claim such furnaces broadly, but I do intend to cover all such forms and modifications thereof as fall fairly within the appended claims.

I claim:

1. A gas furnace having, in combination, a combustion chamber; a condensing chamber spaced therefrom and connected therewith by means of passageways between their upper ends; an upright smoke pipe within said condensing chamber having its intake near the bottom of said condensing chamber; and means directly under said 25 said smoke stack for carrying the condensation from said condensing chamber and smoke pipe out of said furnace by gravity.

2. A gas furnace having, in combination, an upright combustion chamber having a 30 burner contained therein; an upright condensing chamber spaced from said combustion chamber; passageways connecting said chambers near their upper ends; a casing around said chambers spaced therefrom; a smoke pipe passing downwardly through said condensing chamber and having its intake near the bottom thereof.

3. A gas furnace having, in combination,

an upright combustion chamber; means for burning gases within said chamber; an upright condensing chamber mounted alongside of said combustion chamber; passageways connecting said chambers near their upper ends; a casing around said chambers spaced therefrom; a smoke pipe passing through 40 said casing downwardly into said condensing chamber and having its intake near the bottom thereof; a funnel below the intake of said smoke pipe adapted to discharge condensed 45 gases through the bottom of said condensing chamber; a funnel under the bottom of said condensing chamber adapted to receive the discharge from said first mentioned funnel and from the walls of said condensing chamber; a casing around said combustion and 50 condensing chambers and spaced therefrom; warm air discharge pipes leading from the top of said casing; and means for admitting cold air to the lower portion of said casing.

4. A gas furnace having, in combination, 55 an upright combustion chamber; an upright vertical condensing chamber joined to said combustion chamber by means of horizontal tubes between their upper ends; a smoke pipe extending downwardly and having its intake near the lower end of said condensing chamber; a casing around said combustion chamber; said smoke pipe passing downwardly through said casing; funnels for 60 catching the condensation from said combustion chamber and from said smoke pipe; and a pipe for conducting condensation from 65 said funnels and conveying same through said casing.

GEORGE A. SIMMONS.
